UNITED STATES PATENT OFFICE.

OTTO G. HESS, OF LOS ANGELES, CALIFORNIA.

ARTIFICIAL TOOTH.

1,217,866.

Specification of Letters Patent. Patented Feb. 27, 1917.

Application filed September 2, 1914. Serial No. 859,922.

To all whom it may concern:

Be it known that I, OTTO G. HESS, a citizen of the United States, residing at Los Angeles, in the county of Los Angeles and State of California, have invented new and useful Improvements in Artificial Teeth, of which the following is a specification.

This invention relates to artificial tooth or bridge work in which a porcelain facing 10 is provided for the tooth or bridge.

My principal object is to make the best possible joint between the metal backing and the porcelain facing, and at the same time have the facing hide the backing.

15 The accompanying drawings illustrate the invention.

Figure 1 is a perspective view of an artificial tooth constructed in accordance with this invention and adapted to be applied as a 20 crown.

Fig. 2 is a perspective view of the facing and crown backing shown in Fig. 1.

Fig. 3 is an enlarged view of the posterior side of the facing, dotted lines indicating 25 the proportional relative depth of the retaining grooves.

Fig. 4 is a side elevation of the tooth shown in Fig. 1.

Fig. 5 is a vertical section of the tooth as 30 shown in Fig. 1 on line indicated by x^5 , Fig. 3.

Figs. 6, 7 and 8 are cross sections respectively of the artificial tooth on lines x^6 , x^7 and x^8 , Figs. 4 and 5.

35 Fig. 9 is a section of the backing on line x^9 , Figs. 4 and 5, omitting the porcelain facing.

Fig. 10 is a view of the tooth, looking at the cutting edge from line $x^{10}-x^{11}$, Fig. 4.

40 Fig. 11 is a view analogous to Fig. 10 omitting the facing.

The application of the invention to bridge work will be obvious to those skilled in the art, upon examination of the said figures and 45 from the following description.

Arrows on the lines of sections indicate the direction of sight.

The artificial tooth b consists of the two 50 principal parts, the metal backing 8 and the porcelain facing 1.

The details of the metal backing 8 are as follows:

The body of the metal backing 8 has a 55 seat upon its upper face and a pin projecting upwardly from the center of this seat, as is usual in mounting the artificial

tooth against a natural root. The front face of the body of the metal backing forms a seat 11 for the porcelain facing 1, said seat being concaved or curved, when seen in side elevation or vertical cross-section as in Figs. 4 and 5, and said seat being concaved or curved in horizontal cross section, as seen in Figs. 6, 7, 8 and 9. In vertical cross-section the backing extends from the extreme upper 60 end of the facing to the extreme lower end thereof and the surface of the seat is offset forwardly to form the stop 13 about one-quarter of the way down from the top, and interlocking ribs 9 extend forwardly and 65 downwardly from the top of the seat 11 to about three-quarters of the way down thus forming a dovetail groove. The blade portion 10, below the lower ends of the ribs 9 is comparatively thin and is tapered to a lip 70 edge 12 which forms a backing and support for the extreme lower edge of the facing. 75

The details of the porcelain facing 1 are as follows:—

The inner face 7 of the body of porcelain 80 is convex to fit closely the seat 11, there being interlocking grooves 2 to receive the interlocking ribs 9 and form a dove-tail tongue and groove connection between the facing and backing, and there being a shoulder 5 85 below the upper edge 6 to fit the stop 13, and there being extensions 4 fitting against the lower ends of the ribs 9, and there being a cutting edge 3 fitting the lip 12.

The metal of the backing 8 forms a thin 90 sharp edged rim all the way around the seat 11 and the convex face 7 fits within this rim, and the seat 11 is deep enough to receive substantially one-half of the thickness of the porcelain as shown in Figs. 6, 7 and 8, 95 so that the porcelain is well embraced in all directions.

Cement is applied to the joint faces and then the porcelain is pressed upwardly to make the tongue and groove connection, and 100 then the porcelain is pressed firmly into the seat, and after the cement has hardened the exposed surfaces are burnished.

I claim:

An artificial tooth comprising a metal 105 backing having a seat concave horizontally and vertically, there being a horizontal stop in the upper part of the seat and there being interlocking ribs extending downwardly from the ends of the stop and forming a 110 dovetail groove, and the metal around the seat forming a thin sharp edged rim, and

said seat being deep enough from the edge of the rim to receive substantially one-half of a porcelain facing; and a porcelain fitting fitting said seat and having a shoulder 5 fitting said stop and having grooves to receive said interlocking ribs and form a dovetail connection and having extensions fitting against the ends of said ribs, and substantially one-half of the thickness of said porcelain being in said seat beyond the edge of 10

said rim, so that the rim embraces the body of the porcelain all the way around.

In testimony whereof, I have hereunto set my hand at Los Angeles, California, this 28th day of August, 1914.

OTTO G. HESS.

In presence of—

JAMES R. TOWNSEND,

L. BELLE WEAVER.
